A. W. CARREL.

Rotary Churn.

Patented Oct. 25, 1832.

Anthony W. Garrel of Granville, Ohio
Sister's Patent

The Etchale referred to in the following Patent and making part
of the same containing a description in the words of the said Anthony
W. Garrel himself of his improvement in the Churn

To all whom these presents shall come. Be it known that I,
Anthony W. Garrel of Granville in the County of Licking and
State of Ohio have invented a new and useful improvement in
the Churn for making, manufacturing or extracting Butter from milk
or cream, and the following is a full and exact description of the ma-
chine as invented or improved by me. I make a small case suffi-
ciently light to contain the milk or cream, in which is placed the
dasher, and is made and constructed as follows. I make a frame
of a square form sufficiently small to receive in the wash or cheese, in
the side pieces of the frame I place at a regular distance small pieces
of timber pointing inward the ends of which should be far enough
separate to admit a shaft of sufficient strength, then I pass small
pieces of timber thro' the shaft, so as to be able to pass between the pie-
ces in the frame, the shaft being of sufficient length to pass thro' the
top of the churn and a hub or hollow piece of timber and constructed
so as to have a small shoulder below the top of the churn, and made
fast to the frame on the hub. I place a small spur wheel, then
attach a small spur wheel of the same diameter on the end of the shaft
above. the action is given by placing a free wheel of something like
twice the diameter of the spur wheel on a plain attached to the outer side
of the churn so as to be removable.

The free wheel is made to revolve by a crank to the top and bottom
of the shaft. should be firmly, the bottom to work in the center of
the churn, and the top through the top piece of the outer frame.
After churning or breaking the milk or cream, to gather the but-
ter, I attach the frame and shaft when the marks of both are together
or by placing a small pin thro' the hub & shaft when the churn
